UNITED STATES PATENT OFFICE.

WILLARD FRANK. WELLMAN, OF CAMBRIDGE, ASSIGNOR TO FRANK C. PITCHER, OF MEDFORD, MASSACHUSETTS.

ROLLER-BEARING.

SPECIFICATION forming part of Letters Patent No. 515,635, dated February 27, 1894.

Application filed April 26, 1893. Serial No. 471,896. (No model.)

To all whom it may concern:

Be it known that I, WILLARD FRANK. WELLMAN, of Cambridge, in the county of Middlesex and State of Massachusetts, have invented 5 certain new and useful Improvements in Roller-Bearings, of which the following is a specification.

My invention relates to an improvement in roller-bearings for journals, and the object is 10 to surround the journal with a double series of rollers, and provide means for supporting the rollers in their operative relation independently of the journal, so that the latter may be removed without disturbing the roller- 15 bearings.

To this end, the invention consists in the novel features of construction and combinations of parts hereinafter described and claimed.

20 The accompanying drawings illustrate the invention.

Figure 1 shows an end view of the bearing, with one side of the housing removed. Fig. 2 shows a central cross-section through the 25 bearing. Fig. 3 shows a section on line 3-3 of Fig. 1. Fig. 4 shows a section on line 4-4 of Fig. 1.

The same letters of reference indicate the same parts in all the figures.

30 In the drawings: the letter *a* designates the housing which incloses the roller-bearing, and through which the journal *b* extends. The roller-bearings consist of one series *c*, bearing against the curved wall of the housing *a*; and an inner series *c'*, bearing against the journal and the outer series *c*. The rollers comprising the outer series are of larger diameter than those composing the inner series, and each outer roller engages between 35 two of the inner rollers and the outer rollers are thereby held apart, while the friction is taken up by all the rollers and equally distributed among them.

It is desirable that means be provided to 45 support the rollers in their operative relation independently of the journal, so that the latter may be removed without disturbing the rollers, and the rollers may be arranged in position before the journal is introduced into 50 its bearings. The means here shown for accomplishing this consists in a ring *d*, of a size to loosely surround the journal, and annular grooves *d'* encircling the inner rollers *c'* and

receiving said ring. Each of the inner rollers is provided with a groove, preferably located 55 midway between its ends, and the depth of the groove is such as to allow the ring to recede within it and permit a bearing of the journal against the roller. It will be seen that this ring will support the rollers in their operative relation, by reason of its engagement with the grooves in the inner rollers, and at the same time does not impair the effect of the roller-bearings. The journal may be removed, and the ring will still support the 60 rollers.

For the purpose of reducing friction, the ends of the rollers are rounded, as at *c*², so as to reduce the extent of surface bearing against the housing.

The inner sides of the end-plates of the housing are preferably convexed, as shown at *x* *x*, the curved portions being arranged to bear against the ends of the outer rollers at about the centers of the latter, as shown in 75 Fig. 4. These curved bearing-surfaces further reduce the friction attending the contact of the ends of the rollers with the housing, as will be readily seen.

It will be observed that all the rollers are 80 removable and interchangeable, so that, in the event of wear or breakage of the rollers or either of them, new rollers can be readily substituted.

Having thus described my invention, what 85 I claim as new, and desire to secure by Letters Patent, is—

A roller-bearing, comprising in its construction a housing, an outer set of rollers bearing against the housing along the entire length of 90 the rollers, an inner set of rollers between which the outer rollers engage and which bear against the journal and the outer rollers along their entire length, the said inner rollers being provided with annular grooves, and a single ring engaging said grooves closely and 95 encircling the journal, substantially as described.

In testimony whereof I have signed my name to this specification, in the presence of 100 two subscribing witnesses, this 20th day of April, A. D. 1893.

WILLARD FRANK. WELLMAN.
